UNITED STATES PATENT OFFICE.

CHRISTIAN N. SMITH, OF ELGIN, ILLINOIS; ALICE MINNIE SMITH AND LILY IRENE SMITH EXECUTRICES OF SAID CHRISTIAN N. SMITH, DECEASED.

MACHINE FOR BENDING PRINTING PLATES.

Application filed April 12, 1926. Serial No. 101,404.

This invention relates to that class of machines for bending metallic printing plates, in which a rotative printing-plate bending roll is mounted in position to extend over a 5 plate-supporting bed, and a flexible sheet metal plate is interposed between the rotative plate-bending roll and plate-supporting bed, one extremity of such flexible plate or sheet being attached to the roll, and the other 10 extremity to a suitable support, whereby a metallic printing plate to be bent may be placed between the flexible plate and the bending roll and bent by rotating the bending roll while the flexible sheet is held 15 stretched at a tension in position to be bent around the outside of and with the printing plate and between the roll and bed.

The principal object of the invention is to provide a simple, economical and efficient 20 machine for bending metallic printing plates.

A further object of the invention is to provide a machine for bending metallic printing plates which is adapted to permit a printing plate to be held between a rotative plate-bending roll and a plate-supporting bed by 25 means of a flexible metallic sheet or plate one end of which is attached to the bending roll and the other end of which is attached 30 to a suitable support, whereby such flexible sheet is held at a tension and coacts with the bed in holding the printing plate between the roll and bed during the operation of bending the plate.

35 Other and further objects of the invention will appear from the following description and claims, and from an inspection of the accompanying drawings.

The invention consists in the features, 40 combinations, details of construction and arrangement of parts herein described and claimed.

In the accompanying drawings—

Figure 1 is a view in side elevation of a 45 machine for bending metallic printing plates, constructed in accordance with my invention;

Fig. 2 is a plan view of the machine shown in Fig. 1;

50 Fig. 3 is a view in end elevation, showing a back end view of the machine as it would appear when viewed from the right of Figs. 1 and 2;

Fig. 4 is a view in central longitudinal 55 section taken on line 4—4 of Fig. 2, looking

in the direction indicated by the arrows, and showing the construction and arrangement of the rotative bending roll, the printing-plate supporting bed, the flexible metallic sheet or plate of sheet metal extending 60 between the roll and bed and having one end of the said flexible sheet attached to the roll and the other end flexibly connected with a support in front of the roll and bed, and with a metallic printing plate between the 65 flexible sheet and roll as it would appear during the operation of bending the printing plate, the rear part of the machine being broken away, and other parts omitted, for 70 clearness of illustration; and

Fig. 5 is a detail view in section of a plate-bending roll, with a metallic printing plate, flexible backing sheet, and intermediate flexible sheets between the metallic printing plate and outer flexible metallic backing 75 sheet shown in side elevation on said bending roll.

In constructing a machine for bending metallic printing plates in accordance with my invention, I provide a frame 1 having upright legs or frame members 2, transverse frame members 3, and longitudinal frame members or tie rods 4 and 5 which extend along opposite sides of the machine and connect the legs, all forming a strong rigid frame which may be of any desired ordinary and well known or suitable form.

A printing-plate supporting bed 6 is mounted on and may form a part of the frame of the machine. The said bed is disposed horizontally and has a flat horizontal top surface. Located on opposite sides of the bed 6 are parallel horizontal carriage-supporting tracks 7, 7, which may be formed integral with the printing-plate supporting bed. Rotatively mounted on a bending-roll supporting carriage 8, which is slidably supported on and adapted to travel lengthwise of the tracks 7, 7, and from end to end of the printing-plate supporting bed 6, is a printing-plate bending roll or cylinder 9 which is adapted to rotate upon a horizontal axis and extends horizontally over and transversely across the bed 6, the axis of said roll 9 being parallel to the top horizontal surface of the said bed, and the peripheral surface of the roll being adjacent to and located over but spaced from the top surface of the bed and adapted to admit a metallic printing plate 10 to be operated upon or bent, and a flexible 110

metallic sheet or metallic backing plate 11, and suitable non-metallic sheets or pads of compressible or fibrous material, including a moistened pad or sheet of fibrous material, 5 such, for example, as moistened blotter pad material, and one or more dry sheets or pads of compressible moisture absorbing material, if desired, between said roll and bed.

One end of the flexible metallic backing 10 sheet 11 is secured to the periphery of the horizontal rotative plate-bending roll or cylinder 9, by suitable securing means, such, for example, as a flat metallic securing strip 12 which extends longitudinally of the bending 15 roll 9 and along and over the end margin of the flexible metallic sheet or plate 11, and is secured to the periphery of the bending roll by means of screws 13 or other suitable securing means, there being a similar 20 metallic strip 14 mounted on the periphery of the bending roll 9 in parallel relation to the securing strip 12 but between the flexible metallic sheet 11 and the surface of said bending roll. The strip 14 which is inter- 25 posed between the flexible sheet 11 and the bending roll, is adapted to engage the adjacent edge or end margin of the metallic printing plate 10, when such printing plate is inserted between the flexible sheet 11 and 30 the bending roll, and hold said margin in its proper position in removable engagement with the peripheral surface of the bending roll. The inner strip 14 is of sufficient thickness to serve as a gage for positioning 35 the metallic printing plate to be bent, and is adapted to permit the flexible sheet 11 to extend outside of and over said metallic strip or gage 14 and over the entire outer or printing face of the metallic printing plate 40 located between said flexible sheet and bending roll, during the operation of bending the printing plate.

The opposite or front edge or end margin 45 15 of the flexible metallic backing plate or sheet 11 is secured to a stationary support, such, for example, as the forward part 16 of the frame 1 or bed 6, by suitable securing means which is, by preference, adapted to form a yielding connection between the sheet 11 and such support.

A transverse stud-supporting member or 50 bar 17 is secured to or may form a part of the stationary support 16 with which the flexible backing sheet 11 is to be connected. 55 Mounted in suitable horizontal openings in said bar 17 is a series of spring-pressed studs or bolts 18, the outer ends of which are provided with nuts or heads 19 thereon, and the inner ends of which are secured to the forward edge or end margin 15 of said flexible backing sheet 11.

The inner ends of the studs or bolts 18 are secured to the sheet 11, by preference, as follows: A lower forward clamping member or bar 20 having an inner marginal

flange or projection 21 which is adapted to extend under the forward end margin of the flexible backing sheet 11, is mounted in a recessed portion 22 in the forward part of the bed or frame and extends transversely 70 across the bed and beneath said forward end margin of said flexible sheet 11. A top clamping strip or bar 23 is secured to the said forward clamping member or bar 20 by means of screws 24 which extend through 75 suitable perforations in the forward margin 15 of the flexible backing sheet 11 which is interposed between said strips or clamping bars 20 and 23, so that said margin 15 is securely clamped between said bars 20 and 23. And the studs or bolts 18 have their inner ends secured to the clamping bar 20 which is provided with screw threaded openings into which the similarly threaded inner ends of said studs or bolts 18 extend. Compression springs 25 are interposed between the nuts or heads 19 of the studs 18 and the perforated stud-supporting bar 17, and encircle said studs. These springs thus tend to press the studs 18 outward or forward, 90 and exert a constant forward yielding pressure upon said studs. The springs and spring-pressed studs thus constantly tend to pull the forward margin of the flexible backing sheet 11 forward and act to stretch 95 said flexible backing sheet and hold it constantly stretched and at a tension but yieldingly connected with the stationary support.

The plate-bending roll or cylinder 9 may be in the form of a hollow drum having end walls or heads 26 at its opposite ends. Spur gears 27 are fixed to the opposite ends of the drum, or may be formed integrally with the drum heads 26, and are in toothed engagement with a pair of parallel horizontal toothed racks 28, 28, mounted on opposite sides of the bed 6, and, by preference, fixed to the tracks 7 and the side margins of the bed. The toothed racks extend longitudinally of the bed and tracks; and the toothed racks and gears are thus adapted to cause the bending roll 9 to rotate in one direction, so as to cause the flexible backing sheet 11 to be wrapped or wound around that part of the periphery of the bending roll upon which the metallic printing plate is to be bent, as the bending roll and the carriage on which it is supported move toward the front of the machine and bed, and so as to cause the flexible backing sheet 11 to be unwound from the bending roll and release the curved or bent printing plate located between the bending roll and said flexible sheet, when the bending roll and its supporting carriage are moved in an opposite direction, or toward the rear end of the machine and plate-supporting bed. The compression springs 25 being constantly at a tension, tend to stretch and yieldingly hold the flexible sheet 11 taut during the opera- 130

tion of bending the printing plate between the flexible sheet and bending roll, and during the movement of the bending roll and carriage in the direction necessary to release 5 the bent printing plate and to unwind the flexible backing sheet. And the springs and spring-pressed studs are so connected with the flexible backing sheet as to permit the forward or attached end of the latter to 10 move back a short distance during the operation of bending the printing plate and winding the flexible backing sheet onto the roll, and to move forward to initial position as the roll is moved in an opposite direction 15 to release the printing plate and unwind said sheet.

The bending roll 9 is provided with an axle 29, the opposite ends of which are rotatively supported in suitable bearing blocks 30, 20 which are slidably supported on or between parallel ways or guides 31, 32 on the upright end frames of the carriage 8, said end frames being connected by one or more transverse carriage frame members or bars 33, 25 which may extend transversely across and beneath the bed and carriage-supporting tracks. The end frames 34 of the carriage 8 are thus rigidly connected, and a roll-supporting carriage having the required rigidity 30 and strength is obtained. The carriage 8 is provided with bottom end flanges 35 which extend beneath and in sliding engagement with the bottom faces of the tracks 7 on opposite sides of the bed 6, and serve to hold 35 the carriage down in its proper position with respect to the bed notwithstanding the heavy strains to which the carriage and bending roll are subjected in the operation of bending printing plates upon the bending roll or between said roll and the flexible backing sheet and bed.

Suitable means is provided for driving the carriage 8 and rotating the bending roll 9 in opposite directions alternately, as required 45 in the operations of bending printing plates and releasing the same, in accordance with my invention, and may be constructed as follows: A horizontal shaft 35 is journaled in suitable bearings in the upright end frames 34 of the carriage 8, and provided with a pair of spur gear wheels or pinions 36, 36, fixed to said shaft and each adapted to engage an adjacent spur gear wheel 27 on the rotative bending roll 9 already described. 50 Fixed to the shaft 35 is a worm wheel 37; and a worm 38 is mounted on and rotative with but adapted to move longitudinally of a horizontal driven shaft 39, which is provided with an elongated spline 40 adapted to 55 slidably engage the worm 38, which is provided with a suitable key way or slot for receiving and slidably engaging said spline. 60 The worm 38 is in toothed engagement with the worm wheel 37, and is adapted to move with the carriage and plate-bending

roll longitudinally of the shaft 39 while the worm is being rotated by said shaft. The worm shaft 39 is intended and adapted to be rotated in opposite directions alternately, or reversed, and is operatively connected with 70 suitable driving and reversing mechanism and with a motor or source of power which may be of any desired ordinary and well known or suitable form, adapted to enable said worm shaft 39 and the carriage 8 and 75 the plate-bending roll 9 on said carriage to be started, stopped and reversed, or operated in opposite directions alternately, as desired.

The means for connecting the worm shaft 39 with the motor or source of power, and 80 for starting, stopping and reversing the direction of rotation of said shaft 39 and the direction of movement of the carriage and the bending roll thereon, may be constructed, 85 for example, as follows:

An electric motor 41, which may be of the reversible type, such, for example, as a reversible direct current motor, is provided and mounted upon a suitable support 42 on or forming a part of the frame of the machine. A belt pulley 43 is fixed to the worm shaft 39; and a belt pulley 44 is fixed to the main driving or power shaft 45 which may be the motor shaft or may be connected with the motor shaft either directly or indirectly by any ordinary and well known form of connecting or driving mechanism adapted to enable the direction of rotation of the shaft 39 to be reversed either automatically or otherwise. A belt 46 on said belt pulleys, 90 serves in connection with the pulleys, to connect said shaft 39 with the motor or source of power. 95

A starting motor 47, which may be of any ordinary and well known or suitable form, 100 is operatively connected with the motor 41, and provided with suitable switch mechanism for starting, stopping and reversing the motor 41, comprising a starting, stopping and reversing switch lever 48 which is operatively connected with a manually operable shifting or stopping, starting and reversing hand lever 49 by means of a connecting rod 50, said lever 48 being connected with suitable switch mechanism adapted to enable the motor 41 to be started, stopped and reversed, 105 as desired. The starting motor 47 and the switch mechanism connected therewith, are operatively connected with the motor 41 by means of electric conductors 51 and 52, or other suitable connecting means adapted to enable the motor 41 and the driven shaft 39 to be started, stopped and reversed, as desired. Or any ordinary and well known or desired mechanical means for driving and reversing the direction of rotation of the worm shaft 39 and for connecting said shaft with any ordinary or suitable source of power 110 may be employed. As such driving and reversing mechanism is in common use and 115

well known in the art to which this invention relates, it is deemed unnecessary and undesirable that the same should be further described or illustrated herein.

5 Means is provided for operatively connecting the starting, stopping and reversing mechanism, including the switch mechanism above described, with the carriage whereby the lever 49, connecting rod 50, switch arm 10 48, and switch mechanism and reversing mechanism may be automatically operated by the movable carriage 8, and whereby said carriage may be started and automatically stopped, and reversed. In order to enable 15 this to be accomplished a switch-operating bracket arm or tripping member 53 is mounted on the carriage 8 in position to slidably engage the switch-operating connecting rod 50 and to move lengthwise of said connecting 20 rod between stops 54 and 55 which are adjustably mounted upon and adapted to be fixed to said rod. The rear stop 55 is thus adapted to be engaged by the bracket arm 53 when the bending-roll supporting carriage 8 reaches the desired position at the rear extremity of its path of movement, thereby tripping the rod 50 and causing the hand lever 49 and switch arm or lever 48 to be operated in one direction, to stop the carriage. 25 In practice, the carriage is reversed or started by manually operating the hand lever 49. When the carriage is thus started after having been stopped at the end of its rearward movement and caused to move forward, the tripping bracket arm 53 will engage the forward tripping stop 54 on the rod 50 when the carriage reaches the limit of its forward movement, thus causing the hand lever 49 and switch lever arm 48 to be automatically operated in the direction necessary 30 to automatically stop the carriage. The bending of the metallic printing plate having thus been accomplished, the hand lever 49 is again operated manually to cause the carriage to move rearward to plate-releasing position. The curved or bent printing plate is then removed from the bending roll and another inserted, and the operation repeated, 35 and so on for as many times as may be desired.

50 The flexible metallic sheet 11 serves as an outer backing sheet and is of sufficient length to cover the entire bottom side of the metallic plate to be bent and extend forward beyond the front edge of the metallic printing plate and to the front margin of the bed of the machine where said sheet 11 is attached to the machine frame or bed as already described.

55 A similar inner flexible metallic backing sheet 56 is by preference interposed between the outer flexible backing sheet 11 and the metallic printing plate to be bent, said printing plate being between the sheet 56 and the peripheral surface of the bending roll.

An intermediate flexible sheet 57 of relatively thick compressible material, such, for example as rubber or composition containing rubber or equivalent element, is, by preference, mounted between the metallic sheets 11 and 56 and is adapted to yieldingly resist pressure applied to the outer metallic backing sheet and to permit the metallic sheets 11 and 56 to be pressed inward toward the metallic printing plate during the operation 70 of heating and bending the same. The elastic compressible sheet 57, however, acts to hold said metallic plates spaced apart and in yielding relation to each other. Said metallic backing sheets act to prevent the rubbery elastic cushioning sheet 57 from "crawling" and from spreading in direct contact with the metallic printing plate or any sheet material which may be interposed between the sheet 56 and the metallic printing plate. The sheets 11, 56 and 57 serve together to form an armoured or laminated backing plate or structure, or set of backing sheets having the quality of being compressible without causing or permitting either of the 80 outer layers thereof to spread or crawl in the operation of either bending or heating and bending a metallic printing plate.

I also, by preference, place one or more sheets of compressible material including a 95 sheet of moisture-containing material, such as moist paper pulp or similar moistened material 58 between the metallic printing plate and the inner metallic backing sheet 56.

The sheet 58 of paper pulp or similar compressible material in a moist or plastic condition is, by preference, spread in contact with the entire printing side or surface of the metallic printing plate to be bent or heated and bent, and may be said to form a 105 temporary matrix or matrix-like sheet of compressible moisture-containing material, which is compressed and bent against and with the metallic printing plate progressively, and may be dried or partially dried during the operation of bending or heating and bending the metallic printing plate. A sheet of absorbent material 59 in a dry or relatively dry condition as compared with the moisture-containing sheet 58, is laid in contact with the latter, and, by preference on the outside of the said moisture-containing sheet. And a flexible sheet of rubber or similar material 60, which is, by preference, softer than the metallic sheet and harder than the sheet 59 is interposed between the metallic sheet 56 and the compressible sheet 59 of absorbent material. The sheet 59 may be formed of dry wool felt 115 or blotting paper, or similar absorbent compressible material.

In operation the metallic printing plate is bent while in contact with the moisture-containing sheet 58 which is compressed an 120 125 130

- bent simultaneously with the bending or heating and bending of the metallic printing plate and the other sheets above described, thus causing the moisture-containing sheet 58 to be forced into contact with the printing surface of the metallic printing plate, so as to fill all of the interstices and depressions and recesses in the printing side of said printing plate, and form a matrix-like structure which is bent and partially dried while in contact with the printing side of the printing plate and simultaneously with the bending or heating and bending of the latter.
- 15 The metallic printing plate may be bent cold, or may be heated and bent while in a heated condition. And the heating of the printing plate may be accomplished by heating the bending roll, or by heating the bed, or by heating both of said elements, by heating means which may be of any ordinary and well known or desired form, such, for example, as a gas burner or other suitable heating means.
- 25 As such heating means are in common use and well known in the art it is deemed unnecessary to describe the same in detail herein.
- I claim:
- 30 1. In a machine for bending metallic printing plates, the combination of a bed, a carriage movably mounted and adapted to travel over the bed, a plate-bending roll rotatively mounted on and movable with said carriage, a flexible metallic backing sheet having one end attached to the periphery of said bending roll, said sheet being adapted to extend between the bed and the bottom surface of the bending roll and acting to admit a metallic printing plate between said flexible sheet and the bending roll, a stationary sheet-holding member connected with the opposite end of said flexible metallic backing sheet and acting to hold said flexible sheet taut, a spur gear fixed to said bending roll, a toothed rack supported independently of the carriage and in toothed engagement with said spur gear, a spur gear rotatively supported on the carriage and in toothed engagement with a spur gear on said bending roll, and means for rotating said last-mentioned spur gear.
2. In a machine for bending metallic printing plates, the combination of a bed, a carriage movably mounted and adapted to travel over the bed, a plate-bending roll rotatively mounted on and movable with the carriage, a flexible metallic backing sheet having one end attached to the periphery of said bending roll, said sheet being adapted to extend between the bed and the bottom surface of the bending roll and acting to admit a metallic printing plate between the flexible sheet and the bending roll, a stationary sheet-holding member connected with the opposite end of said flexible backing sheet and acting to stretch and hold the same taut, toothed gear mechanism on and rotative with said bending roll, a shaft rotatively mounted on the carriage in parallel relation to the bending roll, a toothed gear on said shaft and in toothed engagement with the gear mechanism on the bending roll, for rotating the bending roll, means for rotating said shaft, and a toothed rack mounted independently of the carriage and in toothed engagement with the gear mechanism on the bending roll and adapted to cause the carriage to travel over the bed when the bending roll is rotated.
3. In a machine for bending metallic printing plates, the combination of a bed, a carriage movably mounted and adapted to travel over the bed, a plate-bending roll rotatively mounted on and movable with the carriage, a flexible metallic backing sheet having one end attached to said bending roll, said sheet being adapted to extend between the bed and the bottom surface of the bending roll and to admit a metallic printing plate between the flexible sheet and bending roll, a stationary sheet-holding member connected with the opposite end of said flexible backing sheet and acting to stretch and hold the same taut, toothed gear mechanism on and rotative with said bending roll, a toothed rack mounted independently of the carriage and in toothed engagement with said gear mechanism, a shaft rotatively mounted on the carriage, a toothed gear on said shaft and in toothed engagement with the gear mechanism on the bending roll, a worm wheel on said shaft, a worm in toothed engagement with said worm wheel, a worm shaft mounted independently of the carriage and in operative engagement with said worm, for rotating the same, and means for rotating said worm shaft.
4. In a machine for bending metallic printing plates, the combination of a bed, a carriage movably mounted and adapted to travel over the bed, a plate-bending roll rotatively supported on and movable with the carriage, a flexible metallic backing sheet adapted to extend between the bending roll and bed and having one end attached to the bending roll, said flexible sheet being adapted to admit and hold a metallic printing plate between the periphery of the bending roll and said sheet, a stationary support, means for attaching the opposite end of said backing sheet to said stationary support, a sheet of compressible moisture-containing material in contact with the printing side of the printing plate and adapted to fill the interstices and depressions in the latter, a sheet of flexible absorbent material between said moisture-containing sheet and the flexible metallic backing sheet, and means for operating the carriage and rotating the

bending roll in opposite directions successively.

5. In a machine for bending metallic printing plates, the combination of a bed, a carriage movably mounted and adapted to travel over the bed, a plate-bending roll rotatively supported on and movable with said carriage, a flexible metallic backing sheet adapted to extend between the bending 10 roll and bed and having one end attached to the bending roll, said flexible sheet being adapted to receive a metallic printing plate between the periphery of the bending roll and said sheet, a stationary support, means 15 for attaching the opposite end of said flexible metallic backing sheet to said stationary support, a sheet of compressible moisture-containing material in contact with the printing side of the printing plate and extending between the latter and said flexible 20 backing sheet, a sheet of compressible absorbent material in contact with said moisture-containing sheet and extending between the latter and the flexible outer metallic 25 backing sheet, flexible sheet material interposed between said sheet of compressible absorbent material and the outer flexible metallic backing sheet, and means for operating the carriage and rotating the bending 30 roll.

6. In a machine for bending metallic printing plates, the combination of a bed, a carriage movably mounted and adapted to travel over the bed, a plate-bending roll rota-

tively mounted on and movable with the carriage, a flexible metallic backing sheet having one end attached to said bending roll, said sheet being adapted to extend between the bed and the bottom surface of the bending roll and acting to admit and hold a metallic 40 printing plate between the flexible sheet and bending roll, a stationary sheet-holding member located adjacent to the opposite end of said flexible sheet, resilient connecting means forming a yielding connection between said stationary sheet-holding member and said flexible sheet, toothed gear mechanism on and rotative with said bending roll, a toothed rack mounted independently of the carriage and in operative engagement 45 with said gear mechanism, a shaft rotatively mounted on the carriage, a gear on said shaft and in toothed engagement with the gear mechanism on the bending roll, a worm wheel on said shaft, a worm in engagement 50 with said worm wheel, a worm shaft rotatively mounted independently of the carriage and in operative engagement with and adapted to rotate said worm, said worm shaft being adapted to permit the said worm 55 to move with the carriage longitudinally of the worm shaft, and means for rotating said worm shaft in opposite directions alternately.

Signed at Elgin, in the county of Kane 65 and State of Illinois, this 23rd day of March, 1926.

CHRISTIAN N. SMITH.
